Attorney

UNITED STATES PATENT OFFICE.

OTTOOMAR VOIGT, OF DUSSELDORF, GERMANY.

DEVICE FOR CLOSING PRESERVE JARS.

Application filed August 19, 1924. Serial No. 732,983.

To all whom it may concern:

Be it known that I, OTTOOMAR VOIGT, a citizen of the German Republic, and residing at Dusseldorf, Germany, have invented 5 certain new and useful Improvements in Devices for Closing Preserve Jars, of which the following is a specification.

My invention relates to a device for closing preserve jars, pots or cans or the like 10 by means of an accessory receiver and an air-pump connected therewith.

The object of my invention is advantageously distinguished from existing devices of this kind by a double valve in which the 15 inlet and delivery valves of the receiver are combined with the inlet and delivery valves of the air pump, which latter are arranged apart and outside the pump, in such a manner that the two valves which are loosely 20 connected with each other can be simply lifted at the same time thus allowing the atmospheric air to rush into the receiver, after having served as inlet and delivery valves for the air pump until sufficient rarefaction of the air in the receiver has been 25 obtained.

In order that the invention be more clearly understood an example embodying the same has been shown in the accompanying 30 drawing in which—

Fig. 1, is an elevation of the object of my invention in longitudinal section, and

Fig. 2, is a view of a modified arrangement partly in section.

On the lid *a* which is loosely set upon the accessory receiver *b*, the cylinder *c* of the air pump is fixed, in which by means of the rod *d* and the handle *e* the piston *f* can be moved up and down. By means of the conduit *g* the air pump is in firm and air tight connection with the housing *h* on the lid. The lid *a* is bored through in the longitudinal axis of the housing, thus forming on the bottom of the latter the contact surface 45 and seating of the pump inlet or suction valve *k* which is provided with a rubber packing *i*. On its upper edge the housing *h* is made air tight by means of the rubber packing *l* of the pump outlet or exhaust valve *n* to which the handle *m* is attached. The valves *k* and *n* are connected by a chain 50 *o* or the like in such a manner that their motion in their longitudinal axis is limited. *p* is an elastic packing ring between the

receiver and the lid, and *q* is the preserve 55 jar or can that is to be closed.

The device works as follows:

The preserve jar, filled and provided with packing ring and lid, is placed into the accessory receiver *b*. Then the lid *a* with 60 the pump and its valves are fitted on the packing ring of the receiver. The piston of the pump is moved up and down. When the piston goes down, the valve *k* is opened and the air from the receiver enters into 65 the cylinder *c* of the pump. At the same time the valve *n* is closed by the suction of the pump. When the piston is moved upwards the valve *k* is closed, whereas the valve *n* opens giving exit to the air. When 70 a greater resistance against the downward motion of the piston shows that the air in the receiver is sufficiently rarefied, both valves *k* and *n* are simultaneously lifted 75 with a jerk by means of the handle *m*, thus allowing the atmospheric air to rush in suddenly and to close the preserve jar or can. It will appear that the valves *k* and *n* are first used as a means for working the air 80 pump and then quite independent of the pump as a means to fill the receiver with air.

The device represented in Fig. 2 is worked in the same way, the bell shaped receiver *b'* being placed upon the packing ring *p'* and covering up the preserve jar on the bottom 85 plate *a'*.

While in describing the invention reference has been made to a particular example embodying the same I wish it to be understood that my invention is not limited to 90 the construction shown in the drawing, and that various changes may be made in the general arrangement of the apparatus and the construction of its parts without departing from the invention. 95

I claim:

1. In a device for closing preserve jars, cans, and the like, an accessory receiver, an air pump connected thereto by a passage for rarefying the air contained in the receiver, 100 and inlet and outlet valves for the pump arranged outside the same and in the connecting passage with the receiver, both of said valves adapted to be actuated to open the receiver to the atmosphere. 105

2. In a device for closing preserve jars, cans and the like, a receiver, an air pump connected thereto by a passage for rarefying

the air contained in the receiver, plural valves arranged in the connecting passage between the receiver and pump and serving as inlet and outlet valves for the pump, and 5 means for substantially simultaneously opening both valves to open the receiver to the atmosphere.

3. In a device for closing preserve jars or cans or the like, an accessory receiver, an 10 air pump rarefying the air contained in the receiver, a lid with a housing on the accessory receiver having a port leading to the atmosphere and a port communicating with the receiver, two valves one above the 15 other in the housing, one valve closing the receiver port against opening inwardly and the other valve closing the atmosphere port and opening outwardly, by a chain connecting the two valves for pulling and draw-

ing, a pipe branching off from the housing 20 between the valves and ending in the upper part of the pump.

4. In a device for closing preserve jars or cans or the like, an accessory receiver, a lid therefor, an air pump on the lid for rarefying the air contained in the receiver, a housing on the lid having an inlet port leading from the receiver and an outlet port leading to the atmosphere, outwardly opening valves in the housing ports, a handle attached to the outer valve for lifting by hand, a chain for pulling or drawing connecting the valves with each other, a pipe branching off from the housing between the two valves and ending in the upper part of the 30 cylinder of the air pump.

In testimony whereof I affix my signature.
OTTOMAR VOIGT.
